UNITED STATES PATENT OFFICE.

FRED STRINGHAM, OF DENVER, COLORADO.

AMALGAMATOR.

1,113,065.

Specification of Letters Patent.

Patented Oct. 6, 1914.

Application filed June 27, 1913. Serial No. 776,092.

To all whom it may concern:

Be it known that I, FRED STRINGHAM, a citizen of the United States, residing in the city and county of Denver and State of Colorado, have invented certain new and useful Improvements in Amalgamators; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to improvements in amalgamators, of the class in which the material under treatment is subjected to the action of liquid mercury. In my improved construction, this material is given a mercury bath, whereby all of the precious metal values which are in a free state are caught, uniting with the mercury by virtue of their affinity therefor, to form an amalgam.

The fact that the precious metal values 25 when in a free state, will unite with the mercury to form an amalgam is well known, but heretofore so far as I am aware, no practicable machine has been produced that will prevent the loss of a considerable proportion 30 of the mercury as well as the amalgam, with the tailings. Consequently heretofore, the mercury bath amalgamators so far as I am aware have been failures.

The distinguishing functional feature of 35 my improved construction consists in the fact that when properly operated, there is no loss of mercury or amalgam with the tailings.

My improved apparatus consists of a pipe 40 or casing inclined to a suitable degree, and in which is mounted a screw conveyer of special construction for carrying the tailings upwardly from the feed extremity of the pipe which is lowermost. This conveyer 45 consists of a shaft or rod to which is applied a spirally arranged blade whose outer edge is toothed to allow the mercury and amalgam to flow downwardly in the pipe and prevent its being carried upwardly and discharged with the tailings, the outer extremities 50 of the teeth being rounded for a suitable distance so that at the points of the teeth of the blades, for a short distance there shall be no conveying or lifting tendency. Furthermore, the shaft of the screw is equipped

with transversely arranged pins having pointed extremities. These pins serve to agitate the contents of the pipe and give the heavier particles of material containing the values, a chance to settle to the lower side 60 of the pipe.

Having briefly outlined my improved construction, I will proceed to describe the same in detail, reference being made to the accompanying drawing, in which is illustrated 65 an embodiment thereof.

In this drawing Figure 1 is a side elevation partly in section showing my improved apparatus. Figs. 2 and 3 are sections taken on the lines 2—2 and 3—3, respectively of 70 Fig. 1, the said sections being viewed in the direction indicated by the arrows adjacent the said lines, the parts being shown on a larger scale. Fig. 4 is an enlarged sectional view of the lower extremity of the pipe or 75 tube forming a part of the conveyer. Fig. 5 is a similar view of the upper extremity of the structure. Fig. 6 is a fragmentary detail view in elevation, showing one of the teeth of the screw thread of the conveyer on 80 a larger scale.

The same reference characters indicate the same parts in all the views.

Let the numeral 5 designate a pipe which is supported in an inclined position and 85 as illustrated in the drawing, consists of a body member 6 whose lower extremity is threaded as shown at 7 into a cast iron terminal member 8 into the top of which is threaded as shown at 9, a feed tube 10 having 90 its upper extremity enlarged and funnel-shaped as shown at 12. The pipe 10 registers with an opening 13 in the lower extremity of the terminal member 8 of the structure. Diametrically opposite the opening 13 is a relatively small opening 14 containing an exteriorly threaded pipe member 15 which is connected as shown at 16 with a casing 17 carrying a valve 18. Into the lower extremity of this casing is threaded as 95 shown at 19 a short pipe member 20, the lower extremity of the latter being threaded as shown at 21 into a second casing 22 carrying a valve 23, a lower discharge member 24 being also threaded into the casing 22. 100 Between the two valves 18 and 23, the amalgam may be trapped after which by opening the valve 23, the amalgam may be removed without permitting the escape of any material above the valve 18. Normally 110

when the apparatus is in use the valve 18 will be open and the valve 23 closed, as best illustrated in Fig. 4 of the drawing.

Eccentrically arranged within the inclined pipe 5 is a screw conveyer 25 comprising a shaft 26 and a blade 27 spirally arranged thereon, the said spiral blade or the screw thread of the conveyer terminating a short distance from the lower ex-

10 tremity of the shaft 26 in order to constantly maintain a body of mercury within the lower extremity of the pipe, of at least sufficient depth to cover the journal 28 of the shaft which enters a socket 29 formed in 15 a plate 30 which is adjustably applied to the lower extremity of the terminal member 8 of the structure. By maintaining a sufficient depth of mercury in the lower extremity of the inclined pipe to constantly 20 fill the socket 29 and surround the journal 28 which extends thereinto, the sand and other material which would otherwise enter the socket and quickly result in destroying the journal, is prevented from coming in 25 contact with the journal at its bearing, thus affording a convenient, economical and effective means of lubrication, since the mercury not only prevents the entrance of any material which would have a tendency to cut 30 the journal, but also performs the lubricating function. The socket plate 30 is adjustably connected with the lower extremity of the terminal member 8 by means of cap screws 31.

35 As illustrated in the drawing, the shaft 25 for the greater part of its length is hollow, its lower extremity however, being equipped with a solid member 32 inserted therein and held in place by rivet pins 33. 40 The upper extremity of the pipe 5 is provided with a permanently arranged closure member 3 perforated to receive the upper portion of the shaft 25, the upper extremity of the shaft however extending beyond the 45 pipe and engaging a bearing 34 which is mounted on an arm 35 secured to the upper side of the pipe by means of rivets 36 or other suitable fastening devices. The bearing 34 is far enough beyond the upper or 50 tailings discharge extremity of the pipe to prevent any of the material within the pipe from coming in contact with the bearing. Beyond this bearing an operating pulley 37 is located.

55 As illustrated in the drawing, the stationary closure member 3 at the upper extremity of the pipe, extends slightly above the center of the latter and is equipped with an adjustable slide valve or cut off 38 which 60 is slotted as shown at 39 to receive the shaft 26 of the conveyer. The cut off valve or plate 38 is adjustably secured in place at the upper extremity of the pipe 5 by means of two bolts 40 which respectively pass 65 through slots 4 formed in the valve plate 38,

the said bolts passing through openings in the closure member 3 of the pipe, and being equipped with arms 43 for convenience of hand manipulation. By adjusting this cut-off valve or plate 38, the tailings discharge 70 level 44 may be regulated at will. Attention is called to the fact that the tailings discharge is an overflow at the upper extremity of the pipe.

The outer edge of the screw thread or 75 spiral plate 27 is toothed as shown at 45, while the outer extremities 46 of these teeth are rounded, as distinguished from flat, in order to prevent any tendency for the outer extremities of the teeth to perform any conveying function, and by virtue of this arrangement, the depth of the material in the lower part of the pipe to the extent of the length of the rounded extremities 46 of the teeth, is not carried upwardly in the pipe, 80 thus giving the mercury and amalgam an opportunity to settle in the pipe and pass downwardly without interruption or counter-acting tendency on the part of the conveyer. Were it otherwise, the mercury as 85 well as the tailings and a portion of the amalgam would be carried upwardly by the screw and lost with the tailings.

The shaft 26 of the conveyer is equipped with transversely arranged pins 47 which 90 perform an agitating function, having a tendency to maintain the water and material under treatment and therefore constituting a pulp, in a homogeneous condition and sufficiently thin and mobile to make it practicable for the mercury which mingles with the 95 entire body of material in the lower portion of the pipe, to be brought into contact with the free metallic values contained in the said material, which values by virtue of their affinity for the mercury unite therewith forming an amalgam which quickly settles in the lower part of the inclined pipe and gradually moves downwardly therein, by virtue of the construction of the outer extremities 46 of the teeth 45 as heretofore explained, since the extremities of these teeth for a depth equal to that of the amalgam in the lower part of the pipe, have no tendency whatever to raise the amalgam in the pipe and offer only slight resistance to its downward movement whereby it may be caught in the trap between the two valves 18 and 23 as heretofore explained.

As illustrated in the drawing, the inclined pipe 5 is maintained in position by supports 48 and 49, their relative heights being determined by the required inclination of the pipe, which inclination may be varied at will and must be made to correspond or harmonize with the quantity of the various materials under treatment. It will, of course, be understood that the supports illustrated are only conventional.

During the operation of the machine, the 130

feed screw is rotated within the pipe 5 by a suitable means as by connecting the pulley 37 at the outer extremity of the feed screw shaft with a motor (not shown) of any suitable character. Before introducing the material to be treated, a quantity of liquid mercury is placed in the lower part of the pipe, being fed thereinto through the feed pipe 10. The quantity of this mercury should be sufficient to completely fill the pipe at its lower extremity, thus making it impossible that any material subsequently fed into the lower extremity of the pipe through the feed pipe 10, may enter without being submerged in the mercury contents of the pipe. Furthermore, it is necessary in order to make a commercially practicable apparatus that the journal 28 which enters the socket 29 as heretofore explained, be submerged in the mercury in order to prevent the sand and other material under treatment from entering the said socket and cutting out the journal within a comparatively short time. It will be difficult to make an ordinary bearing by extending the same beyond the lower extremity of the pipe in the usual manner, which will prevent the entrance of the material from the pipe. In fact, the construction shown, whereby the lower journal of the feed screw shaft enters the open socket 29 in communication with the body of mercury within the pipe, is the only one that has occurred to me, that is entirely feasible and practicable, at least without making the construction much more complicated and expensive.

Assuming that the quantity of mercury within the pipe has its level as indicated by the dotted lines 50 in Figs. 1 and 4, the material to be treated and containing the free metallic values to be caught by the mercury, is fed into the lower part of the pipe 5 through the feed conduit 10, rotary motion being simultaneously imparted to the feed screw in the manner heretofore explained. The action of the feed screw carries the material together with a portion of mercury upwardly in the pipe, the mercury being distributed through the material during a sufficient time to cause all of the free metallic values therein by virtue of their affinity for the mercury, to unite therewith in the form of an amalgam. By virtue of the peculiar construction of the extremities 46 of the teeth 45 of the thread of the feed screw, the amalgam may accumulate in the lower part of the inclined pipe and flow downwardly thereon into the trap between the two valves 18 and 23, since the points of these teeth perform no conveying function.

By virtue of the fact that the thread 27 of the feed screw is interrupted for a short distance at the lower extremity of the screw shaft, the mercury in the lower part of the pipe is always of sufficient depth to sub-

merge the journal 28. Furthermore, by virtue of the fact that the lower part of the upper extremity of the pipe 5 is closed, whereby the only escape for the tailings is above the adjustable cut-off plate 38, there is no opportunity for the escape or loss of any mercury, in case it should be carried to the upper end of the pipe, since in this event, it will naturally assume the lowermost position therein and there will be no possible opportunity for it to climb to the top of the pipe and pass out through the discharge opening 39.

Attention is called to the fact that during the operation of the machine, the feed screw should be rotated with sufficient rapidity, to maintain the material within the pipe 5 in the condition of a comparatively thin pulp and whereby the solid material is equally distributed therethrough, otherwise there will be a tendency for the solid material to pack in the pipe to such an extent as to render the machine useless. I have found in actual use that a machine of this character is exceedingly sensitive and that careful manipulation is required in order to obtain the best results, since the speed of rotation of the feed screw, the quantity of material fed to the machine and the height to which the material is maintained in the feed pipe, must bear proper relation to one another.

In order to regulate or adjust the position of the feed screw within the pipe 5, the socket plate 30 is made adjustable on the lower end of the terminal member 8 of the pipe. In other words, if it is desired to allow the thread of the pipe or rather the teeth, the outer edge thereof, to reach entirely to the lower surface of the pipe, the plate 30 may be arranged in the position illustrated in Fig. 4, while if it is desired to change the position of the screw within the pipe so that the teeth of the screw thread shall travel above the lowermost portion of the pipe, the plate 30 may be raised, whereby the journal 28 is correspondingly elevated and the entire screw shaft tilted. This tilting movement of the feed screw is permitted by virtue of the peculiar shape of the bearing 34 at the upper extremity of the feed screw shaft, and by virtue of the fact that a bushing 51 is applied to the shaft where it engages the bearing. The curved outer surface of the bushing and the corresponding curve of the engaging surface of the bearing is indicated by the dotted line 52 in Figs. 1 and 5. The tilting of the feed screw shaft permitted by the adjustment of the socket plate 30 is an important feature, since it makes it practicable to raise the lower portion of the feed screw from the lowermost side of the casing to a greater extent than the upper portion, and this is as it should be since it is essential that the mer-

cury and amalgam shall have abundant opportunity to move downwardly in the lower portion of the casing, while as the material approaches the upper part of the casing, it is gradually impoverished of its values and the proportion of mercury and amalgam which will accumulate in the upper portion will therefore gradually diminish. Hence, by lifting the lower extremity of the feed screw as may be done by properly adjusting the socket plate 30, the space between the lowermost part of the feed screw and the corresponding part of the casing will gradually diminish from the lower extremity to the upper extremity of the casing.

Having thus described my invention, what I claim is:

1. An amalgamator comprising a pipe inclined to the horizontal, a feed screw journaled in the pipe, the thread of the screw being toothed at its outer edge and the outer extremities of the teeth being rounded to destroy the conveying function at the extreme outer edge of the screw thread, means for feeding the material to be treated, into the lower extremity of the pipe to maintain a pressure head therein, the upper extremity of the pipe being closed to cut off the escape of material except at the upper side, and means for rotating the feed screw, substantially as described.

2. A construction of the class described, comprising a pipe inclined to the horizontal, a feed screw journaled in the pipe and eccentrically arranged to leave a space above the thread of the screw, the entire length of the pipe, the thread of the screw being toothed at its outer edge to destroy the conveying function, means for feeding material to be treated into the lower extremity of the pipe, the upper extremity of the pipe being open on its upper side for the escape of the tailings, the lower portion of the upper end of the pipe being closed, and means for rotating the feed screw, a quantity of mercury being maintained in the lower part of the pipe, substantially as described.

3. The combination of a pipe inclined to the horizontal and having a feed opening at the upper side of its lower end and an amalgam discharge opening at the lower side of its lower end, a pipe communicating with the feed opening and a second pipe connecting with the amalgam discharge, a feed screw journaled in the inclined pipe and comprising a shaft and a plate spirally arranged thereon and having a toothed outer edge, the lower portion of the shaft for a short distance being devoid of the screw thread, means applied to the lower extremity of the feed screw to throw its axis out of parallelism with the axis of the pipe, and the inclined pipe having a discharge opening at the upper portion of its upper end.

4. The combination of an inclined pipe, a

feed screw extending lengthwise thereof, and journaled therein, the pipe being equipped with means for feeding the material to be treated into the lower extremity of the pipe which contains a body of liquid mercury, the upper extremity of the pipe having a tailings discharge opening at its upper side, the outer edge of the thread of the feed screw being toothed and the outer extremities of the teeth being rounded to destroy their conveyer tendency, the shaft of the feed screw being equipped at suitable intervals with transversely arranged pins.

5. An amalgamator comprising a pipe inclined to the horizontal, its lower end being closed and its upper and lower sides of its lower extremity being respectively provided with inlet and outlet openings, a conduit connected with the upper opening for feeding the material to be treated, a second conduit connected with the lower opening to receive the amalgam, a shaft journaled in the inclined pipe and equipped with a spirally arranged plate forming a screw thread which is toothed at its outer edge, the thread being interrupted for a short distance at the lower end of the shaft, the feed screw being eccentrically arranged in the pipe to leave a space above the thread the entire length of the pipe, leaving an overflow opening for the discharge of the tailings.

6. The combination of an inclined pipe whose lower extremity is equipped with means for feeding the material to the pipe and for the escape of the amalgam therefrom, a feed screw journaled in the pipe and extending longitudinally thereof, a space being left above the thread of the screw to form a passage for washing off the tailings from the concentric contents of the tank, the upper extremity of the pipe being equipped with an adjustable cut-off-plate arranged to leave an opening at the upper part of the pipe for the escape of the tailings, the thread of the feed screw being toothed at its outer edge, the points of the teeth being fashioned to destroy their conveying tendency, the feed screw being also equipped at suitable intervals with transversely arranged pins having pointed extremities, the lower part of the inclined pipe containing a body of liquid mercury into which the material to be treated is originally fed, substantially as described.

7. An amalgamator, comprising a casing inclined to the horizontal, a feed screw journaled in the casing and tiltable to throw its axis out of parallelism with the axis of the casing, means applied to the lower extremity of the feed screw to perform the tilting function, means for feeding the material to be treated into the lower extremity of the casing, and means for rotating the feed screw.

8. An amalgamator, comprising a casing

inclined to the horizontal, a feed screw extending lengthwise of the casing, the lower extremity of the casing being equipped with an adjustable plate having a socket which the lower extremity of the feed screw shaft engages, the adjustment of the socket plate being such as to change the position of the axis of the feed screw with reference to that of the casing, the upper journal of the feed

screw shaft being constructed to permit the 10 aforesaid adjustment of the lower extremity of the feed screw, substantially as described.

In testimony whereof I affix my signature in presence of two witnesses.

FRED STRINGHAM.
